UNITED STATES PATENT OFFICE.

JOHN C. DUNTON, OF GRAND RAPIDS, MICHIGAN.

SCREENING MACHINE.

Application filed July 3, 1922. Serial No. 572,387.

To all whom it may concern:

Be it known that I, JOHN C. DUNTON, a citizen of the United States, residing at Grand Rapids, in the county of Kent and 5 State of Michigan, have invented certain new and useful Improvements in Screening Machines, of which the following is a specification.

My invention relates to improvements in 10 machines for screening gravel, coal, crushed stone, cinders, nuts, and other articles of mixed sizes where it is desired to assort the several sizes from each other, and its objects are: first, to provide a means whereby the 15 several sizes of the material being screened may be assorted at one, continuous, operation; second, to provide a means whereby said first object may be attained with a minimum of power requirements; third, to provide a means whereby it will be impossible to "choke" the machine with which the screening is being done, thus avoiding the necessity of stopping the machine to clean 20 out the screening elements; fourth, to provide a means whereby the greatest amount of efficiency may be attained with the least possible amount of wear upon the screening elements, and, fifth, to provide a means whereby the wearing qualities of the screening 25 elements may be greatly increased without extra cost or trouble to the operator.

I attain these objects by the mechanism illustrated in the accompanying drawing, in which Fig. 1 is a sectional elevation of my 30 screen looking to the left from the line 1—1 of Fig. 3. Fig. 2 is an elevation of the machine showing how the driving belt, the elevator belt and the several actuating chains are applied. Fig. 3 is a sectional elevation of 35 the machine looking to the left from the line 3—3 of Fig. 2. Fig. 4 is an elevation of the screening reel upon an enlarged scale. Fig. 5 is an end elevation of the same with one end plate removed to disclose the relative 40 positions of the screening arms. Fig. 6 is a perspective of the reel showing the preferred form of hub upon which the reel arms are to be mounted. Fig. 7 shows the manner 45 of securing the reel arms into the supporting bars on the hub.

Similar reference characters indicate similar parts throughout the several views.

In the accompanying drawing I have 50 shown my machine as in the form of an up-right, rectangular enclosing case which I prefer to have made of metal, or to be metal

lined, so the inflowing gravel, or other material being operated upon, will not be likely to cut into the surface of the case, and roughen it, when passing through the machine. 60

The receiving hopper, formed by the proper construction of the slides 2 and 4, is built into the upper end of the case 1, and is so constructed that the material, upon 65 being deposited into the machine, as at A, will pass through the lower opening of the hopper just back of the reel hubs 8, and will land near the inner end of the reel arms 6, as at a in Fig. 1. The reels are made to revolve 70 in the direction indicated by the arrows, in Fig. 1, so that when the reel arms are passing from the position indicated at a into the position indicated at b, the gravel, etc., will be made to slide upon the arms from the end 75 of the arms towards the hub of the reel, and then downwardly upon the preceding set of arms, as at c, and when these arms have reached the line indicated at d the material, as gravel, etc., will be deposited upon, and 80 will slide off of the chutes 10, thus giving the material at least three siftings with each revolution of each reel, and any surplus that may not be deposited upon the chutes 10 will be carried backwardly by the arms indicated at e, over the slides or chutes f into 85 the line of descending material shown, at B, C, or D, as the case may be, until the fine sand or dust is finally taken up by the worm 90 7 and passed out of the machine. 90

I prefer that the chutes 10 be so arranged that they may be readily removed and replaced, and for this purpose I find it advantageous to hang the inner ends of the chutes upon supporting pins, in such a manner as that indicated at g, so they may be readily raised off of said pins and removed, or inserted and secured. By the use of auxiliary chutes 10' it is possible to so extend the length of the upper chutes as to insure the 100 deposit of each grade or size of material being screened in a pile by itself, thus insuring a perfect grading or assorting of the various sizes of material.

The reels are mounted upon shafts, as 9, 105 or 9', and are made to revolve in the case, preferably, by means of sprocket chains 17 acting upon the sprocket wheels 18. The chains 17 are made to revolve the shafts 9 and 9' by means of any of the well known 110 lines of power transmission, as the belt 19 acting upon the pulley 16 and causing the

shaft 16' to revolve. In this instance I have shown a small gear wheel 15' mounted upon the end of the shaft 16' and meshing with a larger gear wheel, 15, which is mounted upon the shaft E that carries the sprocket wheel 18' so that the shaft E is made to revolve much slower than the shaft 16' revolves. The shafts 16', E, and 13 are mounted upon the girts 3 at the upper end of the case 1 and the shaft 13' is driven by means of the sprocket chain 14, from the sprocket wheel 18', for the purpose of carrying the belt 11, upon which the elevator buckets 11' are mounted, over the drum 12 for elevating gravel, etc. upwardly and into the hopper formed by the walls of the case 1 and the inclined walls 2 and 4.

At 5 I have shown a guard that is made in the case 1 back of the reels and is designed to hold the material being screened in such position that it cannot drop off of the ends of the reel arms, but such as cannot pass through between the arms must be carried over and discharged into the chutes 10. It will be noted, by reference to Fig. 3, that the arms on each lower reel are closer together than those on the reel immediately above it. This is necessary for the proper grading or assorting of the several sizes of material being screened.

In the construction of the reel I prefer that the form of hub shown in Fig. 6 be used. In this construction 8' represents a cast iron, malleable iron, or other suitable hub made 35 to secure to the driving shaft, as 9, which said hub is made the entire length of the reel and is so cast upon the bars 20, which I prefer to have made of Swedish iron, properly prepared steel, soft wrought iron or 40 other suitable material that may be readily prepared for the reception and proper support of the reel arms 6. In preparing the bars 20 for the reception of the arms 6 I drill a series of holes into the edges of said 45 bars, which holes must be of a proper size and depth to receive and firmly hold the arms, and, to assure the firm holding of said arms I drill a hole adjacent to each arm, as indicated at *h*, and pass a pin 50 through each of said holes as indicated in Figs. 6 and 7. I aim to have this pin extend, one half of its diameter, into the side of the arm, so the arm cannot revolve or 55 move endwise in its bearing, and it will be readily understood that if an arm is removed from one position, as at *i*, into position upon the opposite side of the hub, as at *j*, the wearing surface of the arm will be 60 reversed so that I am enabled to, thus, double the wearing qualities of the arms.

I have provided for washing the material as it is passing through the machine in the process of being screened, by means of a water jet, substantially as shown at 21, one or more of which may be utilized, and placed

in such positions in the case as may be desired, and to which water, under pressure, may be conducted through any desired formed or positioned stand pipe, or water supply pipe, as indicated at 22. It will, of course, be understood that these sprays may be located adjacent to any or all of the reels, and may be made to disperse the water in any desired direction.

6' represents a disc that I prefer to have placed at each end of the reel adjacent to, or imbedded into the sides of the case, and F represents supporting plates or hubs thereon for strengthening said discs.

In the construction of the hub 8', shown in Fig. 6, the flanges F are cast integral with the hub and so the ends of the bars 20 will extend slightly into said flanges, thus making the hub and the bars practically integral, and the discs 6' are firmly riveted 85 to the flanges F, as indicated in Fig. 5. On account of the removal of the flange F from the end of the shaft 8' in Fig. 6 I have shown this end of the hub in section, which would follow with the removal of an 90 integral part, as the flange F.

Having thus fully described my invention, what I claim as new in the art, is:

1. In a screening machine for grading the sizes of the elements in lump material, an enclosing case, a series of revoluble reels mounted in said case, said reels made up of a central elongated hub having arms radiating therefrom, said reels positioned one above the other and each lower reel having its arms spaced closer together than the next preceding upper reel, a discharge chute from each reel arranged to deposit each grade of material in a different locality from all other grades of said material, longitudinally of the reels, and means for revolving said reels uniformly for receiving, assorting and discharging the material being screened.

2. In combination with the elements covered in claim 1, the elongated hubs made of cast material, wrought material bars positioned longitudinally of said cast hubs and radiating widthwise therefrom, said bars having holes drilled therein for the reception of the radiating arms, and means for securing the arms firmly, but temporarily into said bars.

3. In combination with the elements covered in claim 1, the elongated hubs made of cast material, a flange cast integral with each end of said hub, wrought bars positioned longitudinally of said hub and made integral therewith and with the flanges at the ends of the hubs, holes formed in the edges of said bars for the reception and support of the radiating arms, and means for securing the arms firmly into said bars.

4. In combination with the elements covered in claim 1, a feeding hopper formed

in the upper end of the case, discharge chutes arranged to carry material from each reel as it is screened, means for elevating the material into the hopper uniformly with 5 the revolutions of the reels.

5. In combination with the elements covered in claim 1, means mounted in the lower end of the case for removing the finer particles from the screen after the

larger lumps have been assorted and dis- 10 charged.

6. In combination with the elements covered in claim 1, means located within the case in positions to spray water upon the material being screened and thoroughly 15 wash the same.

Signed at Chicago, Illinois, June 30 1922.
JOHN C. DUNTON.
